UNITED STATES PATENT OFFICE.

HARRY C. EVANS, OF BRISTOL, PENNSYLVANIA.

CLASP FOR PENCILS, PENS, &c.

SPECIFICATION forming part of Letters Patent No. 508,096, dated November 7, 1893.

Application filed February 15, 1893. Serial No. 462,448. (No model.)

To all whom it may concern:

Be it known that I, HARRY C. EVANS, a citizen of the United States, and a resident of Bristol, in the county of Bucks and State of Pennsylvania, have invented certain new and useful Improvements in Clasps for Pencils, Pens, &c., of which the following is a specification.

My invention relates to improvements in 10 clasps for holding pencils, pens, &c., in a pocket, and my invention consists of a cylindrical ring of soft rubber which is adapted to be placed upon the pen or pencil and which is furnished with a number of radially projecting points which are adapted to engage 15 the sides of the pocket and prevent the pen or pencil from falling from it, and at the same time allow the pen or pencil to be easily placed in or withdrawn from the pocket. If desired 20 my clasp may be attached to and form part of the erasing tip which is frequently attached to the ends of pencils.

In the accompanying drawings, forming 25 part of this specification, and in which similar letters of reference indicate similar parts throughout the several views: Figure 1, is a

side elevation of my clasp; Fig. 2, a plan of Fig. 1, and Fig. 3, a side elevation of a combined clasp and eraser.

My clasp consists of a hollow cylinder of 30 rubber A, which is furnished with a number of radially projecting points, B, preferably arranged in two or more rows. Upon the ends of the cylinder A, I prefer to form raised rings or bands C, which not only give a finish to the 35 clasp, but also strengthen and stiffen the ends.

In Fig. 3, I have shown my clasp furnished at its upper end with a solid head D, which can be used for erasing pencil marks, &c.

Having thus described my invention, I 40 claim—

The combination in a pencil clasp of a hollow cylinder of rubber adapted to be carried upon the end of the pencil, two or more rows of radially projecting points carried by said 45 cylinder and a solid piece of rubber carried by the upper end of said cylinder and forming an eraser.

HARRY C. EVANS.
